(57) **CLAIM**

The ornamental design for a lens, as shown and described.

DESCRIPTION

FIG. 1 is a top, right, front perspective view of a lens, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top, right, rear perspective view thereof; and,

FIG. 9 is an exploded top, right, front perspective view of the lens of FIG. 1, shown in an environment of use with an exemplary headlamp.

The dash-dash-dash broken lines in the drawings illustrate portions of the lens that form no part of the claimed design. The additional dash-dash-dash broken lines only seen in FIG. 9 are for the purposes of disclosing environment and form no part of the claimed design.

1 Claim, 6 Drawing Sheets
